(57) **CLAIM**

The ornamental design for a foldable solar power box, as shown and described.

DESCRIPTION

FIG. 1 is a front view of a foldable solar power box in a closed position showing our design.

FIG. 2 is a back view thereof.

FIG. 3 is a right side view thereof.

FIG. 4 is a left side view thereof.

FIG. 5 is a top view thereof.

FIG. 6 is a bottom view thereof.

FIG. 7 is a perspective view of the inside of the foldable solar power box in an opened position; and,

FIG. 8 is a perspective view of the outside of the foldable solar power box in the opened position.

The stippling shown in FIGS. 1, 2 and 8 represents surface treatment.
